(57) **CLAIM**

The ornamental design for a case for a personal computer, as shown and described.

DESCRIPTION

FIG. 1 is a front side perspective view of a case for a personal computer in accordance with our new design; FIG. 2 is a front side elevational view of the case for a personal computer illustrated in FIG. 1;

FIG. 3 is a rear side elevational view of the case for a personal computer illustrated in FIGS. 1 and 2;

FIG. 4 is a left side end elevational view of the case for a personal computer illustrated in FIGS. 1-3;

FIG. 5 is a right side end elevational view of the case for a personal computer illustrated in FIGS. 1-4;

FIG. 6 is a top plan view of the case for a personal computer illustrated in FIGS. 1-5;

FIG. 7 is a bottom plan view of case for a personal computer illustrated in FIGS. 1-6; and,

FIG. 8 is a front side perspective view of a case for a computer illustrated in FIGS. 1-7 with the pair of covers moved to opened positions.

The portion of the computer case and parts located underneath the covers in FIG. 8 are shown in broken lines for illustrative purposes only and form no part of the claimed design.
